UNITED STATES PATENT OFFICE.

WILLIAM A. J. LOWE, OF JOHNSON CITY, TENNESSEE, ASSIGNOR TO UNIVERSAL MANUFACTURING COMPANY, OF JOHNSON CITY, TENNESSEE, A CORPORATION OF TENNESSEE.

DISPLAY STAND.

Application filed February 23, 1921, Serial No. 447,146. Renewed June 1, 1923.

To all whom it may concern:

Be it known that I, WILLIAM A. J. LOWE, a citizen of the United States, residing at Johnson City, in the county of Washington and State of Tennessee, have invented new and useful Improvements in Display Stands, of which the following is a specification.

This invention relates to store furniture, particularly to display devices, and has for its object the provision of a display stand for exhibiting fruit, vegetables, and the like, the stand having its lower portion so constructed as to hold baskets in inclined position, it being provided intermediate its ends with a plurality of shelves having retaining rails and adapted to support fruit of various kinds, and having its upper end formed with a plurality of hooks upon which are suspended bunches of bananas.

An important object is the provision of a device of this character including a plurality of uprights which form the main support and which are made in sections detachably connected so that the device may be knocked down for convenience in transportation or storage.

An additional object is the provision of a device of this character which will be neat and attractive in appearance, which will permit the display of a large variety of articles in limited space, which will be sanitary, efficient and durable, and a general improvement in the art.

With the above and other objects and advantages in view, the invention consists in the details of construction to be hereinafter more fully described and claimed and illustrated in the accompanying drawings in which—

Figure 1 is a perspective view of one form of my device showing it in use and displaying fruit and vegetables,

Figure 2 is a cross sectional view on the line 2—2 of Figure 1,

Figure 3 is a detail longitudinal sectional view through one of the units and through the means for holding one of the shelves,

Figure 4 is a vertical sectional view through the bottom portion showing the supports for holding baskets,

Figure 5 is a cross sectional view on the line 5—5 of Figure 1, and

Figure 6 is a perspective view of a modified form.

Referring more particularly to the draw-

ings and especially to Figures 1 to 5, I have shown my device as comprising a plurality of upright bars 10 which are inwardly offset toward their upper ends, as clearly shown, and which have their upper terminals threaded. Connected with the lower ends of these uprights are pipe couplings 11 within the lower ends of which are secured casters 12. The side branches of these couplings are connected by horizontal members 13 which form the rectangular bottom frame of the device.

The numeral 14 designates intermediate uprights which are offset inwardly intermediate their ends, as shown, and which have their lower extremities threaded for connection with units 15 which are connected with the threaded upper ends of the uprights 10 and the function of which is to permit disassembling of the device. The upper ends of the uprights 14 are threaded for connection with pipe couplings 16 within which are threaded the lower ends of the top uprights 17 which have their upper ends bent downwardly, as shown at 18, and terminating in hooks 19. The pipe couplings 16 have horizontal branches within which are threaded diagonally disposed pipe sections 20 connected by a cross coupling 21. These sections 20 hold the upper ends of the frame in proper spaced relation.

Secured upon the highest points of the bent portions 18 are longitudinal and transverse strips 22 and 23, respectively, and also connected at these same points are diagonal strips 24 which serve to brace the upper end of the structure.

The numeral 25 designates a shelf which rests upon the diagonal pipe sections 20 and which is secured thereto at its corners by bolts 26 extending through the sections. This shelf is provided at its edges with upstanding rails 27.

Disposed within the confines of the uprights 14 and arranged in spaced relation to one another are shelves or trays 28 which are similar in construction and each of which is formed from a sheet 29 of material, preferably enameled metal, having secured upon its underside diagonally arranged strips 30. The ends of these strips are bent downwardly, as shown, to provide lugs 31 which are disposed against the uprights 14 and secured thereto, as by means of bolts 32. These shelves are all provided at their edges

with upstanding rails 33 which provide retaining means for fruit or vegetables placed upon the shelves.

At their intermediate portions the lower uprights 10 are connected by longitudinal and transverse strips 34 and 35, respectively. The strips 35 serve as supporting means for a shelf or tray 36 which has secured upon its bottom longitudinal reinforcing strips 37 having their ends bent upwardly and formed into hooks 38 which engage over the strips 35.

Disposed at the lower portion of the frame between the uprights 10 are hoops 39 which are arranged in inclined position and secured together in pairs, as shown. The outermost edges of each pair of hoops are secured together by strips 40 which extend inwardly of and are bolted to the uprights 10, as shown at 41. Connected with the lowermost points of the hoops are strips 42 which extend downwardly and which are bolted to the members 13, as shown at 43.

In the use of the device baskets 44 of circular form are engaged within the hoops 39 and will be supported thereby in inclined position, as clearly shown in Figure 1, and these baskets are adapted to contain preferably vegetables. Fruits or vegetables of different kinds are placed upon the shelves 25, 28 and 36 and will be very effectively displayed. The hooks 19 are designed for suspending bunches of bananas.

Referring to the form shown in Figure 6, it will be seen that the structure is slightly different. In this form I make use of a pair of rear uprights 45 which are vertical, and front uprights 46 which have their upper portions inclined rearwardly. The lower ends of the uprights 45 are screwed in the couplings 47 which are connected by a pipe section 48 and into which are screwed pipe sections 49 connected with T's 50 screwed onto the lower ends of the uprights 46. The lower ends of the uprights 46, below the T's 50, are connected by a strip 51. Connected with the couplings 47 outwardly of the uprights 45, are members 52 which have their outer ends bent downwardly, as shown at 53, and these downwardly bent ends and the lower extremities of the uprights 46 carry casters 54. The numeral 55 designates braces which are secured to the rear uprights 45 and to the members 52. The down-turned ends 53 are connected by a strip 56 and are connected to the lower ends of the front uprights 46 by strips 57. The numeral 58 designates inclined brace strips which are secured to the rear uprights 45 and to the center of the member 48. In this way a very strong and rigid structure will be provided.

The numeral 59 designates hoops, one of which is disposed between each forward upright 46 and the brace bar 55 and two of

which are disposed between the front uprights 46 and the opposite sides of the end hoops are bolted to the bars 55. The highest points of the end hoops have secured thereto depending strips 61 which are secured to the members 49. The front hoops are connected, as shown at 62, and have their highest points secured to the rear uprights 45. These hoops 59 are designed to support baskets in exactly the same manner as in the previously described form.

Screwed upon the upper ends of the uprights 45 and 46 are units 63 and 64, respectively, into which are screwed uprights 65 and 66, respectively. At their upper ends the uprights 65 are received into couplings 67 which are connected by a pipe section 68. The upper ends of the uprights 66 are bent rearwardly and are connected with the couplings 67. Screwed into the couplings 67 are the topmost uprights 69 which have their upper extremities extended forwardly and laterally, as shown, and provided with hooks 70. The upper ends of these uprights are connected by a strip 71 and are connected to the center of the member 68 by a V-shaped strip 72.

The numeral 73 designates railed shelves which are disposed between and secured to the front and rear uprights in exactly the same manner as in the previously described form and constructed in identically the same way.

It is observed that the use of this form is the same as the use of the other form, the only difference being in the details of construction. In both forms of the device it will be seen that there is ample provision for displaying fruits, vegetables or any other desired articles in a very neat and attractive manner. As the device is constructed entirely of metal it is apparent that it may be quickly and easily cleansed and that it may be kept in a highly sanitary and thoroughly satisfactory condition so as to present the wares in an enticing manner.

While I have shown and described the preferred embodiment of my invention it is of course to be understood that I reserve the right to make such changes in the form, construction, and arrangement of parts as will not depart from the spirit of the invention or the scope of the subjoined claims.

Having thus described my invention, I claim:

1. A display rack comprising a frame formed as a plurality of uprights connected at intervals by longitudinal and transverse bars, certain of said uprights terminating in downwardly extending portions provided with hooks, a plurality of hoops supported between said uprights at the lower portions thereof and arranged in inclined position, said hoops being adapted to support baskets, and a plurality of shelves se-

cured between the intermediate portions of said uprights.

2. A device of the character described comprising a plurality of uprights formed in sections detachably connected and connected at intervals by transverse and longitudinal bars, and a plurality of shelves arranged in spaced relation between the up-

rights, each shelf including a sheet of metal, strips secured upon the underside of the sheet in diagonal relation and having their outer ends down-turned to provide lugs engaging against the uprights, and bolts passing through said lugs and the uprights.

In testimony whereof I affix my signature.

W. A. J. LOWE.
